UNITED STATES PATENT OFFICE.

RALPH D. MERSHON, OF NEW YORK, N. Y.

ALTERNATING-CURRENT APPARATUS.

1,077,626.

Specification of Letters Patent.

Patented Nov. 4, 1913.

Application filed April 27, 1910, Serial No. 557,980. Renewed May 24, 1913. Serial No. 769,767.

To all whom it may concern:

Be it known that I, RALPH D. MERSHON, a citizen of the United States, residing at New York, in the county and State of New York, have invented certain new and useful Improvements in Alternating-Current Apparatus, of which the following is a full, clear, and exact description.

This invention relates to polyphase electrical apparatus, such as motors and generators, rotary converters, etc., and its chief object, stated generally, is to provide means whereby such apparatus may be operated on single-phase circuits, with results comparable to those obtained on polyphase circuits.

To this and other ends the invention consists in the novel features of construction, arrangements of parts, and combinations of elements hereinafter described.

Several convenient and effective embodiments of the invention are illustrated diagrammatically in the accompanying drawings, and referring now thereto, Figures 1, 2 and 3 show in simple diagram various ways of operating a polyphase motor on a single-phase circuit. Fig. 4 is a diagrammatic representation of the method illustrated in Fig. 3, but with non-inductive motor circuits. Figs. 5 and 6 are vector diagrams representing various electrical conditions in the apparatus. Figs. 7, 8 and 9 are diagrams illustrating three ways of applying my invention when the motor-circuits are non-inductive, or have their reactance neutralized so as to make them equivalently non-inductive. Fig. 10 is a diagram representing the electrical equivalent of an induction motor. Fig. 11 is a diagram illustrating a mode of applying the invention, when the motor-circuits are inductive, without neutralization of their reactance. Fig. 12 is a diagram illustrating a modification of the latter scheme.

As is well known, polyphase apparatus may be operated on a single-phase circuit by employing in connection with the apparatus a suitable combination of phase advancing and retarding devices, or, in general, phase-modifying means, for example capacity and reactance. Thus in Fig. 1 the three-phase motor M may be run on current from the single-phase source S by connecting across one of the phase windings a

condenser 1 and across another a reactance 55 2. Similarly, a two-phase, or quarter-phase, machine may be operated on a single-phase circuit, as by means of the arrangements shown in Figs. 2 and 3. In the first of the last-named figures the two phases of the 60 motor are in series, with the capacity 3 and the reactance 4 in shunt to the respective circuits; while in Fig. 3 the two motor-circuits are independently connected to the source, one through the reactance, 5, and 65 one through the capacity, 6. The arrangement shown in Fig. 3 is also illustrated in Fig. 4, in which, however, the motor circuits are represented by the adjustable non-inductive resistances 7, 8. If now the values 70 of the reactance 9 and capacity 10 are properly proportioned to the resistances 7, 8, the currents in the two phase-windings (represented by 7, 8, as previously stated) will be in quadrature. This condition may 75 be represented by the vector diagram Fig. 5, in which E is the impressed E. M. F., *oa* and *oc* are the components of E. M. F. consumed in the resistances 7, 8, respectively and the other sides of the two triangles, *ab* 80 and *cb*, are the components of E. M. F. consumed in the reactance 9 and capacity 10 respectively.

Suppose now that the values of 7 and 8 be varied by the same amount, simultaneously. The triangles in the vector diagram will change correspondingly, for example to one or another of the forms shown in full lines in Fig. 6; a diminution giving the triangles *oeb* and *obd*, for instance, and an increase giving the triangles *ofb* and *ogb*. It will therefore be seen that if the power taken by the resistances, or in other words the current therethrough, be varied by varying the resistances alone, the quarter-phase 95 or quadrature relation of these components will be destroyed, giving a relation greater or less than 90°, as the case may be. The quadrature relation may, however, be restored by increasing or decreasing, as may 100 be required, the reactance and capacity components of E. M. F., by varying the values of the reactance 9 and capacity 10. On the other hand the quadrature relation will be maintained, when the power taken by the 105 two resistances is varied, if the power-variation is produced not by varying the resistances but by varying the voltage impressed

on the entire combination; since in this case the relation of resistance and reactance on the one hand, and of resistance and capacity on the other, remains unaltered. This is 5 equivalent to varying the impressed voltage as the square root of the power required.

The maintenance of a proper phase relation in the polyphase circuits (for example 90° in two-phase apparatus, 60° in three-phase, etc.), is a matter of the utmost importance in the operation of polyphase apparatus on single-phase circuits, and it is accordingly the chief object of my present invention to provide means for accomplishing 15 the desired maintenance of phase-relation.

In carrying out the invention the desired control may be effected automatically, in various ways. For example it may be dependent upon variation of the total amount 20 of power taken by the motor. This method is illustrated in Fig. 7, in which a quarter-phase motor is shown at 11, with phase windings 12, 13, fed from a single-phase 25 source 14 through a transformer 15. 16 is a device operating on the wattmeter principle, having a pivoted shunt coil 17 connected across the transformer terminals, and a stationary series coil 18 in the motor 30 circuit. The shunt coil has an arm 19 playing over a series of contacts 20 brought out from the transformer, and the arm is in series with the circuit of the field coil 18. The 35 circuit of the shunt coil contains the usual non-inductive resistance 21. The external reactance and capacity are shown at 22 and 23 respectively.

From the foregoing the operation of the system will be readily understood.

40 As the total power taken by the motor varies, in one direction or another from a predetermined value which for convenience may be termed the normal value, the shunt coil 17 will turn and the arm 19 will move over 45 the taps or terminals 20, cutting transformer turns in or out of the motor circuit as the case may be; it being understood, of course, that in designing the apparatus due regard will be had to the fact that the transformer 50 turns cut in or out must be such as to keep the impressed voltage equal to $\sqrt{2}$ times the power required by the motor. It may here be noted that the external reactance 22 and capacity 23 are in series with the respective 55 motor-circuits, as in Fig. 3, this arrangement being selected merely for the purpose of exemplifying one method of connecting these elements when my invention is employed.

By reference to Fig. 6 it will be seen that 60 when the phase-relation departs from normal not only do the angles between the impressed E. M. F. and the components vary, but the relative values of the components vary also. Thus under normal conditions 65 the components *ab* and *oc* are in phase and

equal, as are also *oa* and *cb*. Under abnormal conditions they are out of phase and unequal. Under normal conditions *oa* and *ab* are in quadrature and equal, while under abnormal conditions they are unequal 70 though still in quadrature; likewise *oc* and *cb*. These variations may be availed of for the purposes of my invention by employing 75 as the controlling device one which depends for its operation upon change in the phase relation of the components mentioned, or upon change in their values. An example of the first of these methods, in which variation in the phase-relation of the components mentioned is the controlling factor, is illustrated in Fig. 8. Here, for the sake of simplicity in the diagram, the motor circuits are shown as simple non-inductive resistances 24, 25. An auxiliary two-phase motor 26 is employed, one phase of which is connected across *cb* and the other across *oa*, as indicated in the figure. Under normal conditions, when these components are in phase, the auxiliary motor exerts no torque and is therefore stationary; but when the phase 80 relation is disturbed the auxiliary motor develops torque and the pinion 27 on the rotor will advance (or retract, as the case may be) the rack 28 carrying the contact member 29 across the terminals of the variable reactance 30 and variable capacity 31, cutting reactance and capacity in or out of the motor circuits until the normal phase 85 relation of the components *ab* and *oc* is restored, whereupon the auxiliary motor 90 ceases to exert torque and the contact member comes to rest. In this scheme the torque 95 developed by the adjusting device (the auxiliary motor 26), and hence its speed of operation, depend upon the degree of distortion or departure from the normal phase relation, and diminish as the adjustment brings about an approach to normal conditions. That is, the adjusting device slows 100 up, more or less, as the phase relation approaches the normal. It will also be observed that the direction of movement of the controlling device depends upon the direction of the abnormality, so to speak. Thus 105 a condition which would bring about a condition represented by the triangles *oeb* and *odb*, for example, would produce a movement of the contact member 29 in one direction (toward the left in Fig. 8), and a condition represented by the triangles *ofb* and *ogb* would cause movement of the contact 110 member in the opposite direction. 115

As previously stated, difference in the values of the components involved may be employed for the purpose of control. This 120 scheme is illustrated in Fig. 9, in which, as in Fig. 8, an auxiliary motor, 32, is provided to move the contact member 33 across the variable reactance 34 and capacity 35. The 125 operation and direction of movement of the 130

auxiliary motor are controlled by a reversing switch 36, whose arm 37 is actuated by a lever 38 having its ends attached to the cores of two solenoids 39, 40. One of these coils, 39, is connected across cb , and the other, 40, across oc , as indicated in the figure. It will now be seen that as long as these components are equal, and their difference therefore zero, the pull exerted by one solenoid will balance that exerted by the other, and the switch-arm will remain in its neutral position. When, however, the values of the components change so that they are no longer equal, one solenoid will 10 over-balance the other and throw the switch, starting the motor in the corresponding direction. As soon as the components referred to are again equal the solenoids will again be in balance and the switch will be 15 restored to neutral position. In the scheme illustrated in Fig. 9, as in Fig. 8, the reactance 34 and the capacity 35 are in series with the respective circuits of the main motor, (these circuits being represented by the 20 non-inductive resistance 41, 42), but of course the invention is not limited to that particular mode of connection.

It will be noted that throughout the foregoing explanation of Figs. 8 and 9 the polyphase power circuits of the motor are assumed to be non-inductive. If they are not they may be made equivalently non-inductive (for example by the employment of condensers 43, 44, Fig. 7, in the manner described in my copending application Ser. No. 557,979, filed of even date herewith) if the motor has a short-circuited secondary or if such resistance as is introduced thereinto does not carry with it any reactance or 35 capacity; that is, if the reactance elements of each circuit of the motor are constant. Under such circumstances all the polyphase power circuits can be controlled by a single device, (an auxiliary motor for example), 40 as in Figs. 7, 8, and 9. But if the desired regulation is to be effected regardless of the condition of the secondary, whether inductive or non-inductive, short-circuited or containing variable resistance or capacity, 45 etc., it is, in general, necessary to have a regulating device or mechanism for each polyphase power circuit in which regulation is required. Moreover, in the preceding description the external reactance and capacity 50 were in series with the circuits of the motor, but they may be in multiple with the respective circuits. The preferred method of applying my invention under such conditions will now be described, confining the 55 description, for the sake of brevity, to a three-phase motor. It will, however, be understood that the invention is not restricted to any particular number of phases.

Referring to Fig. 10, it will be recognized 60 that this figure represents the electrical

equivalent of a three-phase induction motor with external reactance and capacity, connected as in Fig. 1, for example, to enable it to operate on a single phase circuit. Such resistance as would be introduced into the 70 motor secondary is represented by the adjustable resistances 45, 46, 47. In series with these resistances are the reactances 48, 49, 50, representing the variable reactances which might be introduced as 45, 46, 47 are 75 varied. 51, . . . 62 inclusive are reactances of the primary and secondary, due to stray field; and 63, 64, 65 represent reactances each taking current equal to the no-load magnetizing current of its respective motor-circuit. It may be noted here that 48 . . . 65, any or all of them, might be capacity so far as the general solution of the problem is concerned; but in practice they would usually be reactances, 80 as indicated. In any case the total current taken by any one circuit of the motor may be considered as split up into two components 90° apart. One of these components is in step with the electromotive force impressed upon the motor circuit, and represents the power expended in the resistance 45, 46, or 47, as the case may be, and in such resistance as the reactances in such circuit might have. This component of current we 95 may denote generally by r . The other component of current, which is 90° away from the E. M. F. impressed upon the motor circuit, represents the component of current for the magnetizing of the reactances in the 100 circuit, and may be denoted generally by R .

The proper analytical investigation shows that, in order to have balanced three-phase in the circuits of Fig. 10 when single-phase E. M. F. is supplied to the terminals 6, 67, 105 the following conditions must obtain:

1. The current of the external reactance 68, which current may be denoted by R' , plus the total reactance current, R , of the motor circuit across which 68 is connected, 110 must be equal to $\sqrt{3}$ times the work current r of such circuit. That is, $R' + R = r \sqrt{3}$. Or, if 49, 55, 56, 57, 58, 64 represent capacity, $R' - R = r \sqrt{3}$.

2. The current, C , of the external capacity 69, minus the total reactance current R , of the circuit across which 69 is connected, must be $\sqrt{3}$ times the work current r of such circuit. That is, $C - R = r \sqrt{3}$. Or, if 50, 59, 60, 61, 62, 65 represent capacity, $C + R = r \sqrt{3}$.

Now consider phase A, (Fig. 10), which has the reactance 68 in parallel with it. If the resistance 46 of this phase be increased 125 the current r therethrough will be decreased. Hence, in order to keep the relation $R' + R = r \sqrt{3}$, the reactance 68 must be increased so that its current will diminish; and if the decrease of the work current r con- 130

tinues, a point will be reached at which, in order to preserve the above relation, the reactance 68 must be increased till its current is zero. At this point $R = r\sqrt{3}$. But suppose 46 be still further increased, with corresponding diminution of its current r . It may be impracticable or even impossible to vary R at this stage, in order to preserve the $\sqrt{3}$ ratio, but we can in effect neutralize R by substituting capacity for the external reactance 68; an expedient which is equivalent to making the current R' negative and giving it the proper absolute value to keep $-R' + R = r\sqrt{3}$. It may be noted that the same reasoning applies when 49, 55, 56, 57, 58, 64 represent capacity if at the beginning 68 also represents capacity and changes to reactance at the point where $R = r\sqrt{3}$.

In phase B, which has the external capacity 69 in parallel with it, $C - R$ must equal $r\sqrt{3}$, as previously stated. Hence as the work current r of this phase diminishes, the condenser current C must be decreased. If capacity were connected to the motor secondary, then C would have to be still further decreased. If the value of the capacity in the secondary were increased, the current to 69 would have to be decreased coincidentally until it had fallen to zero, and if the increase of the secondary capacity were carried far enough 69 would have to be replaced by reactance.

The relations thus briefly outlined can be readily availed of for the purposes of my invention, for example by the means illustrated in Fig. 11. In this figure 70 designates the polyphase motor (three-phase), and 71 is the source of single phase current. The motor secondary may be short-circuited or have inserted in it resistance, capacity, or reactance, or any two or all three of the same, a short-circuited secondary of the squirrel cage type being shown in the figure, designated by S. Across one of the derived phases a variable reactance 72 and a variable capacity 73 are connected, and across the other derived phase are similar reactance and capacity, designated by 74 and 75 respectively. These two phases might have a common terminal at 76, with either delta or a winding, but for the sake of clearness a terminal for each phase at this point is shown. The terminal contacts 77, 78, of the reactances and condensers just mentioned, are arranged to coöperate with two pivoted sectors 79, 80, so that the movement of sector 79, for example clockwise from the position shown in the figure, will cut out more and more of the multiple reactances (thereby decreasing the current of the external reactance, in accordance with the explanation given above), and finally cut in more and more capacity. Movement in the opposite direction will of course reverse the opera-

tion. In the other phase, counter-clockwise movement of sector 80 from the position shown cuts out more and more of the multiple capacity 75 and finally cuts in more and more of the multiple reactance 74. Of course such movement of the sector, past one set of taps and onto the next set, as would put the sector in contact with both sets, would accomplish an equivalent result, but the consequent increased loss in the reactance-capacity device makes the other scheme in general more desirable. Suitably located stops u, u , are provided to limit the movements of the sectors.

The sectors are actuated, through the instrumentality of worms and worm-gears, by small auxiliary induction motors 83, 84, (three-phase in the present instance), whose operation, and direction of rotation, are controlled by reversing switches 85, 86. The arms 87 and 88 of these switches play between contacts 89, 90, 91, 92, in the circuits of the auxiliary motors, and are actuated by the devices 93, 94, so that engagement of the switch arm 87 with the contacts 89, for example, will cause the auxiliary motor 83 to run in one direction, while engagement with the opposite contacts will cause movement in the opposite direction. The operation of switch 86 is of course exactly similar. The condensers 95 and 96, in the circuits of the auxiliary motors, enable these motors to run in either direction, as will be readily understood.

The switch arms 87, 88 are connected to and actuated by the devices 93, 94. As these latter are similar in construction and operation a description of one will serve for both.

The device 93, pivoted at its center, has three arms 97, 98, 99, carrying the voltage-coils 100, 101, 102, respectively, and adjacent to these latter are three stationary current-coils 103, 104, 105. The current coil 103 is in series with the motor circuit (through one of the taps at 76 in Fig. 11) so that the current of the motor circuit passes through it; and through the adjacent voltage-coil 100 passes a current proportional to the voltage impressed upon the corresponding circuit of the motor but in quadrature therewith (lagging 90°) by reason of a suitably proportioned reactance 106. The torque, which may be denoted by T , produced between coils 100 and 103 is therefore proportional to the quadrature component of the motor-circuit current. The total current made up of the motor-circuit current and the current from the reactance-capacity 72-73 passes through the current-coil 105 while through the adjacent voltage-coil 102 passes a current whose voltage is proportional to and in step with the E. M. F. impressed on the motor-circuit. The torque of coils 102 and 105, which torque may be

70

75

80

85

90

95

100

105

110

115

120

125

130

denoted by t , is therefore proportional to the power-current component, r , of the total current; and it is to be noted that the coöperating coils just mentioned take account of the total power consumed, in the phase in which they are connected, including the loss in 72—73. The current R' , of 72—73, also passes through the current coil 104, and through the adjacent voltage coil 101 passes a current proportional to the impressed E. M. F. but in quadrature with it by reason of a suitably proportioned reactance 107. Hence the torque, T' , of the two coils last named, is proportional to the quadrature component of the current from 72—73, such current being all quadrature current except for the small component accounting for the loss in 72—73. The number of turns in coil 105 is $\sqrt{3}$ times the number in each of the other two current coils. Now the coils 100—103, 101—104, are so connected and arranged that their torques are additive when the current in the motor-circuit lags, (that is, when R is reactance current), while the coils 102—105 are so connected that their torque opposes the sum (algebraic) of the torques of the other two sets of coils. We therefore have the relation $T' + T = t$, when $R' + R$, (or $-R$ if R is condenser current), $= r \sqrt{3}$. The device 93 is then stationary, with the switch arm 87 in its neutral position, and hence the auxiliary motor 83 is inactive. But suppose r should vary, decreasing, for example, to a certain value. The device 93 will then be unbalanced, turning clockwise, for example, and the switch arm will bridge the upper pair of contacts, 89. The auxiliary motor 83 will then instantly start in the corresponding direction, turning the sector 79 clockwise and cutting out more and more of the multiple reactance 72, even throwing in the capacity 73 if necessary, until $R' + R$ is again equal to $r \sqrt{3}$. At this point the polyphase currents in the motor 70 are again in balance, the torque t is again equal to the algebraic sum of torques T' and T , and the springs x, y at once return the device 93 to its neutral position, thereby breaking the circuit of the auxiliary motor 83 and stopping the sector 79. Now suppose the work current to increase from its last value. The operation described will be reversed, and the sector will turn counter-clockwise until the balanced polyphase relation in the main motor is restored.

During the above operations the device 94 turns counter-clockwise and the auxiliary motor 84 turns the sector 80 in the same direction; it being remembered that in this phase, $C-R$, (or R if R is condenser current), $= r \sqrt{3}$ when the desired polyphase relation of currents and E. M. F's in the main motor obtains. It will be observed that in this phase the direction of the current

through current coil 105' with respect to the direction through the coöperating voltage coil is the opposite of that in the other phase, since the auxiliary motor and sector of the one phase must in general move in a direction opposite to that in the other phase. 70

From the foregoing it will be seen that the devices 93, 94 take account of variation of the work current and the change in the internal reactance current R (or capacity current, as the case may be) incident to such variation, and through the instrumentality of the auxiliary motors 83, 84, and the reactance-capacity combinations, 72—73, 74—75, maintain the balanced polyphase relation in 80 the polyphase circuits of the motor 70

Inasmuch as two of the voltage or shunt coils in each controlling instrument, 93, 94, have reactances (or capacity, if desired) in series with them these instruments will be 85 affected by change of frequency. If such change is not great the effects will be immaterial, otherwise the results may be more serious. This difficulty may be avoided by using an instrument in which the coils 100, 90 103, and 101, 104, (acting on the dynamometer principle), are replaced by stationary coils acting on metal sectors, in the manner of an induction watthour meter, which are fastened to the appropriate arms of the 95 pivoted controlling device. This scheme is illustrated in Fig. 12, in which the external reactance-condenser combinations 72^a—73^a, 74^a—75^a, the auxiliary motors 83^a, 84^a, the sectors 79^a, 80^a, reversing switches 85^a, 86^a, 100 and coils 102^a, 105^a, and other elements, correspond exactly, in construction and operation, to the similarly lettered parts in Fig. 11. The arms 97^a, 99^a, of the controlling instruments 93^a, 94^a, carry metal plates 105 or sectors 108, 109. On one side of these plates are stationary current coils 110, 111, and on the other side stationary voltage coils 112, 113, the latter, and the voltage-coils 102^a, having non-inductive resistances 110 114 in series with them.

From the principles of the induction watthour meter it will now be seen that the torque of each induction element on each controlling instrument in Fig. 12 will be 115 proportional to that component, of the main current passing through the respective induction element, which is in quadrature to the impressed E. M. F., just as in the case of the corresponding elements of Fig. 11; 120 but that the torques on the arms, and hence the resultant torque on each device, will be independent of the frequency.

The foregoing explanations have been confined to induction motors, but it will be 125 understood by those skilled in the art that the invention may be applied to other types of motors as well, and by simple reversal may be employed to derive single phase power from a polyphase generator. The 130

generator may then be loaded symmetrically and its full polyphase capacity can be realized, instead of the reduced capacity resulting when single-phase power is taken from 5 one phase only.

It will also be understood that the invention is not limited to the forms herein specifically illustrated and described but is capable of various other embodiments without departure from its proper spirit and 10 scope.

I claim:

1. The combination of electrical apparatus having polyphase circuits, adjustable 15 phase-modifying means connected with said circuits to enable the apparatus to operate on a single phase circuit, and automatic means for adjusting said phase-modifying means to maintain a given phase-relation 20 in the polyphase circuits of the apparatus.
2. The combination of a single-phase circuit; electrical apparatus connected therewith and having polyphase circuits; adjustable reactance and capacity connected with 25 the polyphase circuits to give a desired phase-relation therein; and automatic adjusting means for the reactance and capacity, to restore the desired phase-relation when the same is departed from.
3. The combination of a single-phase circuit, electrical apparatus connected therewith and having polyphase circuits, external 30 reactance and capacity connected with the polyphase circuits for the production of a desired phase-relation therein, and automatic means for varying the external reactance and capacity as the current in the 35 said apparatus varies, whereby to maintain the desired phase-relation.
4. The combination of an alternating current motor having polyphase circuits, phase-modifying means connected with the motor for the production of a desired polyphase 40 relation in said circuits when the motor is supplied from a single-phase source, and automatic means for controlling the phase-modifying means to maintain the desired 45 phase-relation in said polyphase circuits.
5. The combination of an alternating current motor having polyphase circuits, external reactance and capacity connected with 50 said circuits for the production of a given polyphase relation therein, and automatic means for varying the external reactance 55 and capacity to maintain the given phase relation in said polyphase circuits.
6. The combination of an alternating current motor having polyphase circuits, external phase-modifying devices connected with 60 the motor for the production of a given polyphase relation in said circuits when the motor is supplied from a single-phase source, and automatic means, dependent for operation 65 upon variation of the power- and reactance- components, for regulating the

phase-modifying devices to maintain the desired polyphase relation in said polyphase circuits.

7. The combination of an alternating current motor having polyphase circuits, adjustable phase-modifying devices connected therewith for the production of a desired polyphase relation in said circuits when the motor is supplied from a single-phase source, an auxiliary motor operatively connected with the phase-modifying devices to adjust the same, and automatic controlling means for said auxiliary motor, dependent for operation upon departure from said desired polyphase relation. 70

8. The combination of a main alternating current motor having polyphase circuits, adjustable phase-modifying devices connected therewith for the production of polyphase currents with a given polyphase relation in said circuits when the motor is supplied from a single-phase source, an auxiliary motor associated with the phase-modifying devices to adjust the same, and automatic means for controlling the auxiliary motor, dependent for operation upon variation in the power- and reactance-components, to maintain the given phase-relation of said polyphase currents. 85

9. The combination of an alternating current motor having main and derived-phase circuits; an adjustable phase-modifying device for each derived-phase circuit; and automatic devices, for adjusting the phase-modifying devices; dependent for operation upon variation of the power- and reactance-components, to maintain a given polyphase relation of currents in the motor circuits. 95

10. In an alternating current motor having main and derived-phase circuits, the combination with a derived-phase circuit, of an adjustable reactance-capacity device, for producing a desired relation of the current of said device and components of current in the said derived-phase circuit, and automatic adjusting means for said device, dependent for operation upon departure from said desired relation. 105

11. In an alternating current motor having main and derived-phase circuits, the combination with a derived-phase circuit, of an adjustable reactance-capacity device connected therewith, an auxiliary motor associated with said device to adjust the same, and automatic controlling means for the auxiliary motor, dependent for operation upon variation of components of current in the said derived-phase circuit, whereby to maintain a desired relation of said components and the current of the reactance- 110 capacity device. 120

12. The combination of an alternating current motor having main and derived-phase circuits, adjustable phase-modifying means connected with the motor for the 125

maintenance of a desired polyphase relation in said circuits, and automatic means, independent of change of frequency of current supplied to the motor, for adjusting 5 said phase-modifying means.

13. The combination of an alternating current apparatus having polyphase circuits, adjustable phase-modifying means for producing a desired polyphase relation in said 10 circuits when the apparatus is operated on a single-phase circuit, and automatic adjust-

ing means for the phase-modifying means, independent of the frequency of said currents and dependent for operation upon departure from the desired polyphase relation 15 in said polyphase circuits.

In testimony whereof I affix my signature in the presence of two subscribing witnesses.

RALPH D. MERSHON.
